Inventor

Charles T. Brady,

By Charles T. Brady

Attorney

UNITED STATES PATENT OFFICE.

CHARLES T. BRADY, OF DETROIT, MICHIGAN.

DESIGN FOR A DENTAL WALL LAMP.

Application filed November 11, 1926. Serial No. 19,670. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for Dental Wall Lamps, of which the following is a specification, reference being had to the accompanying drawing, forming part thereof.

Fig. 2 is side elevation of the same.

I claim:

The ornamental design for a dental wall lamp, as shown.

CHARLES T. BRADY.
